Primary Examiner — Richard Kearney*Assistant Examiner* — Anthony Vincent Rotolo(57) **CLAIM**

The ornamental design for an LED strip light, as shown and described.

DESCRIPTION

FIG. 1 is a front perspective view of an LED strip light, showing our new design;

FIG. 2 is a front view thereof;

FIG. 3 is a rear view thereof;

FIG. 4 is an enlarged floor plan on its left;

FIG. 5 is an enlarged floor plan on its right;

FIG. 6 is a top view thereof;

FIG. 7 is a bottom view thereof; and,

FIG. 8 is a local enlarged view of FIG. 1.

The broken lines throughout the drawing figures depict portions of the lamp that form no part of the claimed design.
